UNITED STATES PATENT OFFICE.

GEORGE D. HAWORTH, OF CHICAGO, ILLINOIS.

CORN-PLANTER.

SPECIFICATION forming part of Letters Patent No. 602,903, dated April 26, 1898.

Application filed May 21, 1897. Serial No. 637,639. (No model.)

To all whom it may concern:

Be it known that I, GEORGE D. HAWORTH, of Chicago, in the county of Cook and State of Illinois, have invented certain new and useful Improvements in Corn-Planters, of which the following is a specification.

This invention is embodied in a complete modern corn-planter having mechanism for drilling the corn, mechanism for planting in check-rows, mechanism for dropping by foot or hand, automatic reeling mechanism, a marker to form impressions in the soil to guide the driver, &c., it relates to various details and peculiarities in connection with the different features of the planter, it is exemplified in the structure hereinafter described, and it is defined in the appended claims.

In the drawings forming part of this specification, Figure 1 is a plan showing as well as can be illustrated in a single view the various parts combined in an operative planter. Fig. 2 is a plan of the wire-reeling mechanism, showing the conditions under which the wire is guided to the extreme inner side of the reel. Fig. 3 is a similar view showing the conditions under which the wire is guided to the extreme outer side of the reel. Fig. 4 is a side elevation of the wire-reeling mechanism. Figs. 5, 6, and 7 are details illustrative of the action of a friction-developer which forms a part of the reeling mechanism and possesses some novel characteristics that aid in effecting one of the principal objects of such mechanism. Fig. 8 is a front elevation of the reeling mechanism. Fig. 9 is a plan showing the drilling mechanism in detail and also showing parts of the foot-drop mechanism. Fig. 10 is a plan showing the foot-drop mechanism in detail and also showing parts of the drilling mechanism. Figs. 11 and 12 are front elevations of details of the drilling mechanism. Figs. 13 and 14 are side elevations of details of the foot-drop and drilling mechanisms, illustrating certain co-operative peculiarities thereof. Fig. 15 is a side elevation of the mechanism used to lift the runner-frame. Fig. 16 is a representation of the under surface of a check-rower arm. Fig. 17 is a bottom view of a block or casting, one of which is located at each joint and at the swinging end of the check-rower arm. Fig. 18 is a side view of a joint-casting in connec-

tion with the bars of the arm and with the guide-rollers. Fig. 19 is a vertical section through a swingable draft-hitch, by means of which the side draft of the marker-bar may be automatically neutralized. Fig. 20 is a plan of the marker-bar and the side-draft neutralizer. Fig. 21 is a rear elevation of the marker-bar and its connections. Fig. 22 is a side view of the cut-off plate of a seedbox, showing a knocker-finger thereon for dislodging corn from the seed-cells of a planter-disk. Fig. 23 shows a seed-disk in section and a knocker-finger in operative position with relation thereto. Figs. 24 and 25 are details illustrating the operation of the knocker-finger. Fig. 26 is a plan of the under side of the cut-off plate with the finger swung thereon. Fig. 27 is a plan of the under side of the cut-off plate, the finger, and a seed-disk, all in operative correlation.

The type of planter shown in Fig. 1 of the drawings and in which the various improvements are in this instance embodied is that commonly known as the "Haworth cross-wire," but in most particulars the invention is independent of the general structure of the planter, and this particular style is shown merely as a preferred form, sufficient to enable persons skilled in the art to reduce the various details of the invention to practice and to apply them to any desired form of planter. With this explanation it may be stated that the planter-frame comprises an axle-bar 10, on which carrying-wheels 3 are mounted; a rear cross-bar 11, with which covering-wheels 4 are connected, an intermediate cross-bar 9, which connects the seedboxes 2, and a front cross-bar 8, with which the front ends of runners 1 connect. A tongue 5 connects with the front cross-bar and with the intermediate cross-bar 9. Bars 80 extend obliquely upward from the cross-bar 9 over the wheel-frame, from which they are supported at their rear ends. A seat 6 is carried on bar 7, which forms a rearward extension of bars 80. The seedboxes are connected with the axle-bar in a manner permitting independent vertical motion of the runner-frame and the wheel-frame, and the different parts are suitably braced.

One feature of the invention relates to the reeling mechanism for the wire, and it resides

partly in provision whereby the wire may be made to actuate the planting mechanism while being reeled and unreeled and partly in means for disposing the wire evenly on the reel.

A reel 18 is made of any desired form and proportion, and it is mounted on a shaft 19 in a manner to slide lengthwise thereon and partake of the rotary motion thereof. The connection between the reel and its shaft is typified by a feather and slot, but it preferably consists of a finger 30, fixed onto the end of the shaft outside the reel and extended parallel with the shaft into sliding engagement with an arm or spoke of the reel-frame. The shaft 19 is journaled in a sleeve 20, which is carried on an approximately vertical rocking bar 23. The rocking bar is connected with a cap 41, which fits loosely over and is detachably secured to a wheel-spindle 42. (Shown in Fig. 4.) A brace-bar 37 connects with the upper end of a continuation of the reel-carrying bar 23. It extends inward over a wheel of the planter and downward to a hook 39 on the axle-bar, and it has on its inner end an eye 38, which detachably engages the hook on the axle-bar. Another brace-bar 28 connects swingably with the sleeve 20, and it extends forward and connects detachably with a check-rower arm. The reel is provided on each side with a circumferentially-grooved collar 36, (see Fig. 3,) by means of which the reel may be shifted sideways while turning. Straps 25 are bent at their outer ends to engage the groove of collar 36. They extend one on each side of the upper extension of bar 23 and the upper portion of the brace-bar 37, and they connect at their inner terminations with a lever 40 on brace-bar 37. The lever is connected pivotally with the brace-bar in position to be readily accessible to the driver on the planter-seat, and it provides means whereby the reel may be shifted inward or outward on its shaft, and the entire reel-frame may be rocked forward and backward. To hold the hooked ends 27 of straps 25 into engagement with the groove of collar 36, a groove or slot is formed by means of a parallel rod 24 on sleeve 20, and a bolt 26 extends from one strap to the other through the slot or space between the rod and the sleeve.

The mechanism employed to transmit motion from a planter-wheel to the reel in reeling the wire and to retard the reel in unreeling is the same as that described by me in Letters Patent of the United States No. 534,474, issued February 19, 1895, except for details in the friction-developer, which enable the reel to be used on either side of the planter, and such mechanism comprises a sprocket-wheel 29, connected with a planter-wheel 3, a pulley 21 on the inner end of the reel-shaft 19, a chain 22, driven by the sprocket-wheel 29 and running over the pulley, an arm 31, adapted to bear against the chain in reeling and against the pulley in unreeling, and a spring

to impart yielding pressure to the arm. The spring is in housing 32, which is connected with the arm by means of a detachable link 33, and its extended end 34, or the extended end of the rod that bears against it, connects with a clamp-link 35, which engages the lower end of bar 23 and firmly engages such bar by automatic cramping action when the spring exerts a pull on its extended end.

The arm is swung loosely on a pin 51, which extends inward from upward continuation 23^a of the reel-supporting bar 23, and it has on opposite sides chain-bearing surfaces 31^a, a central pulley-engaging finger 31^c, and a perforated head 31^b, with which the spring engages. When the wire is reeled up with the reel located on one side of the planter, one bearing-surface 31^a is made to engage the chain. When the wire is reeled from the other side of the planter, the other bearing-surface engages the chain, and the central finger 31^c engages the periphery of the pulley whenever the wire is unreeled from either side of the planter. While the wire is being reeled, the friction-developing arm occupies the position with relation to the pulley shown in Fig. 7, and in preparing to unreel the arm is detached from the spring, swung upward, as suggested in dotted lines in Fig. 5, the finger 31^c is passed over a flange of the pulley by sliding the arm on pin 51, the arm is lowered until the finger bears against the concavity of the pulley, and the spring is reconnected with the arm.

The check-rower arms are connected with the planter in a manner permitting a limited amount of horizontal swing across the winding-surface of the reel, and they are in horizontal alignment with the under side of such surface. In other words, the under surface of the reel is approximately in horizontal alignment with a check-rower arm when operatively mounted, and the arm has a limited amount of swing across the face of the reel. The brace-bar 28 performs the double function of sustaining the reel-frame from the check-row arm and of swinging the check-row arm horizontally when the reel-frame is rocked vertically.

In unreeling the wire the chain 22 is removed, the finger of the friction-developer is made to engage the pulley, as hereinbefore described, the spring is adjusted to develop the required degree of friction, the wire is run off the reel and through the check-row mechanism, and the dropping mechanism of the planter is actuated as the wire is laid out. In reeling the wire the chain is replaced, the friction-developer is made to engage the chain, the wire is fed to the reel through the check-row mechanism, thereby actuating the drop-plates of the planter, and the handle 40 is manipulated by the driver in a manner to evenly distribute the wire on the reel. The reel is shifted lengthwise of its shaft in order to obtain a part of the motion necessary to distribute the wire over all portions of the periphery of the reel, and the residue of such

- motion is obtained by swinging the end of the check-row arm across the face of the reel. In the first instance the lever 40 is swung inward and outward sidewise of the planter.
- 5 In the second instance the lever and the entire reel-frame are swung forward and backward lengthwise of the planter, and the complete wire-guiding action is a complex commingling of the two sets of motions, each of which is 10 auxiliary and complementary of the other. It is difficult to get sufficient swing in the check-row arm to carry the wire from side to side of the reel. The reel cannot be shifted outward sufficiently far to carry the wire to 15 its extreme inner side without developing undesirable strain on the reel-frame, and so the two mechanisms complement one the other.
- A prominent function of the reel—that of 20 actuating the planting mechanism while reeling and unreeling—depends more on general peculiarities of the reel and the check-row mechanism and the correlation thereof than upon the specific characteristics of the reel 25 already described and those of the check-row mechanism, which will form the subject for a subsequent description. The reel may be driven and controlled by means substantially different from those disclosed and the 30 wire may be distributed by different means, or not at all, without impairing the identity of the broad idea involved in this feature of the invention and which is embodied in such correlation of planter, reel, and check-row 35 mechanism that the reel may be used on either side of the planter interchangeably, and the check-row mechanism may act as a guide to supply the wire to the reel in act of reeling and receive it from the reel in act of unreeling. To 40 provide for these requirements specifically, a hook 39 is attached, one to each side of the planter-frame, in position to engage the eye 38 of brace-bar 37. The brace-bar 28 is swingable on the sleeve and adapted to engage 45 with either of the check-row arms. The cap 41 is adapted to engage either of the wheel-spindles, and the friction-developer arm 31 may be used with the reel in either position. Furthermore, the check-row mechanism bears 50 such relation to the reel that the wire may be passed through the mechanism without materially affecting the operation of the reel, and the specific peculiarities of such check-row mechanism will hereinafter appear.
- 55 The particular check-row mechanism shown and described is that known as "cross-wire;" but it is obviously not impracticable to apply the general idea of the simultaneous reeling and planting or unreeling and planting 60 to side-wire planters either by guiding the wire across the planter or otherwise directing it to the check-row mechanism and from there to the reel.
- The reel-spider is capable of translatory 65 transposition from one side of the planter to the other, and so the wire on the reel always bears the proper relation to the check-row
- mechanism, no matter on which side the reel is mounted. If this were not so, if the reel required turning in shifting it from one side 70 of the planter to the other disarrangement of the wire with relation to the check-row mechanism would result to an extent to make it impossible to effect the desired result.
- The check-row arms shown in this instance 75 possess the not unusual peculiarity of swinging forward to receive the wire and swinging backward to discharge it, and in addition they have some novel characteristics which increase their utility. They each consist of 80 a bracket 43, which is adapted to be connected with the planter somewhat as shown in the drawings and which has sidewise-projecting lugs 43^a. (See Fig. 16.) A casting or block 47 is pivoted on the upper side of the bracket 85 on a bolt, as 87, which extends through the bracket and the block, and it has downward-extending studs 47^a, which engage the lugs of the bracket and limit its swing. Underneath the bracket an end of a bar 44 is swung 90 on bolt 87, and above the bracket a bar 45 sets rigidly in the block and extends in the same general direction as bar 44. The upper bar 45 is shorter than the lower bar, and it terminates fixedly in another block 47, which 95 is essentially the same as that hereinbefore described. Another bolt extends through the second block, through the lower bar 44, the upper bar 45, and through an end of a third bar 46, which is interposed between bars 44 and 45 and which extends inward some distance beyond the second block. The block at the conjunction of bars 44 and 45 with bars 46 also has downward-extending studs 47^a, and these engage the inward-extending end 105 of bar 46 and limit the swing of such bar. The bars 44 and 45 form a truss member having a limited amount of horizontal swing, and the extending end 44^a of bar 44 forms a stiffening-support, on which bar 46 swings to the 110 extent permitted by the studs on the block with which it is pivotally connected. A third block of a character substantially identical with those hereinbefore described, except that the studs 47 may be omitted, is fixed onto 115 the outer or swinging end of bar 46, and each of the blocks has a pair of upward-extending rollers 48, between which the wire 52 runs. Each pair of rollers has a guard-finger 49, which extends from the upper end of one 120 roller across the space between the pair and terminates adjacent to, but not contiguous with, the opposite roller.
- The guards, disposed in the manner shown and described, hold the wire between the 125 rollers while the planter is operating and provide for raising the wire out of the arms whenever necessity for detachment arises. Further utility of the arms resides in the specific provision for limiting the swing of the different 130 members, in the truss construction of the inner member, and in the means employed to sustain the outer member.
- The check-row mechanism consists of the

swingable arms, forked levers 50, pivotally connected with the planter, one adjacent to each arm and in position to receive the check-row wire, a rock-plate 53, with which the 5 forked levers connect through rods 58 and 59, a forked rock-arm 56, which is actuated by the rock-plate, and a rod 83, connecting the rock-arm with the shake-bar 12 of the planter.

The foot-drop mechanism comprises a rock-frame 60, pivoted centrally at 61 on bars 80 of the planter and having pedal extensions 62 and 63, one to the right of and behind the pivot and one to the left of and in front of the pivot. The rock-frame has an upward extension 64, from which a rod 82 extends to an arm of rock-plate 53. When the foot-drop is used, the rods 58 and 59 are disconnected from the rock-plate, rod 82 is connected therewith, and motion is imparted to the shake-bar through the rod 82, the rock-plate 53, the rock-arm 56, and the rod 83 whenever frame 60 is oscillated by the feet of the driver.

The drilling mechanism consists of a shaft 66, Figs. 1, 11, and 12, journaled transversely of the planter-frame and having a sprocket-wheel 105 (seen only in Fig. 1) on its outer end. The sprocket-wheel is adapted to be driven with a chain run from the reel-driving sprocket-wheel 29, and so the shaft when operated receives motion from a planter-wheel. The inner end of the drill-shaft has clutch projections, as 68. A crank-arm 67 is mounted slidably on the end of the shaft, and it has recesses adapted to receive the clutch projections. A pitman 69 is connected with the swinging end of the crank-arm, and its extended end is recesses sidewise to engage a vertical bearing of an L-lever 70. The L-lever is pivoted on a bracket-casting 65, which 35 forms a bearing for one end of the drill-shaft. One of its ends is diverted downward and then extended horizontally to form the pitman-support 71 and provide a vertical engagement bearing for the recess of the pitman, and a rod 72 connects its other end with the shake-bar of the planter. As the drill should not operate when the runners of the planter are out of the ground provision is made to disengage the drill-shaft from the 40 shake-bar when the runners are raised. This provision consists of the slidable crank-arm, which forms a clutch member co-operative with the projections on the shaft, a U-bar 73, connected with the crank-arm, a vertical rock-arm 74 in line with the shaft, a link 75, connecting the rock-arm with the U-bar, and a finger 77, adapted to rock the arm 74 as the 45 runner-frame is raised and thereby carry the crank-arm out of engagement with the projections on the shaft. The rock-arm 74 has a slot 76, which extends obliquely upward when the crank-arm is in clutch with the shaft. One end of finger 77 extends into the slot of the rock-arm, and the other end thereof is 50 connected rigidly with the rock-frame of the foot-drop movement. The rock-frame 60 has a cross-bar 81, which extends below the seat-

brace bars 80, as shown in Figs. 9 and 10. When the runners of the planter are in the ground, the conditions of the clutch-actuating mechanism are as shown in Figs. 11 and 13, the end of the finger being in the lower end of the slot of the rock-arm and the crank-arm being in clutch with the shaft. As the runners are raised the bars 80 swing toward the horizontal, the cross-bar 81 of the foot-drop frame is depressed, the extended end of the finger is correspondingly raised, the rock-arm 74 is swung away from the end of the shaft by the action of the finger in the inclined slot, and the crank-arm is drawn from contact with the projections of the shaft. (See Figs. 12 and 14.) When the runners are lowered, the clutch-recesses of the crank-arm may not coincide with the projections on the shaft, and in that case the finger will remain in the upper portion of the slot until motion of the shaft brings the clutch members into coincidence, when action of gravity, aided, if necessary, by a spring, as 79, will draw the 90 finger downward, rock the arm 74, and force the clutch into engagement. To provide for the motion in the crank-arm lengthwise of the shaft, the pitman has the lever-engaging recess formed in one of its sides. Such recess extends parallel with the endwise motion of the crank-arm, and the L-lever has the horizontal extension 71, on which the recessed end of the pitman may slide. When the crank-arm is moved lengthwise of the shaft, the pitman moves correspondingly on the extension of the L-lever, and the recess of the pitman is sufficiently deep to permit such motion without disengaging the pitman from the L-lever. When the drill mechanism is used, rod 83 of the check-row movement is disconnected from the shake-bar and motion is imparted to the dropping mechanism through the sprocket-gearing, the shaft, the crank-arm, the pitman, the L-lever, the rod 72, and the shake-bar. When the foot-drop mechanism is used, the finger 77 is detached from the rock-frame 60.

In using cross-wire planters the wire is taken up on one side of the planter and run off from the opposite side. The side from which the wire is run off is the side from which the marker-bar extends. The check-row mechanism is in front of the marker-bar. Ordinary marker-bars extend beneath the wire, and turns are made at the ends of the field without disconnecting the wire from the planter. This condition of affairs has heretofore required the marker-bar to be detached from the planter prior to turning around and to be reattached afterward, an operation that has objectionable features, and it is the purpose of one feature of this invention to overcome such objections. To this end the marker-bar is made in two parts 95 and 89, pivotally connected at their conjoining ends. The part 95 has a bracket 96 which joins with the planter-frame below the seat thereof in a manner permitting universal swing, but pre-

cluding rotation of the bar. The part 89 carries a marker 88 on its outer end, and its inner end lies alongside the outer end of part 95 and is pivotally joined thereto by a horizontal bolt 90. The extreme inner portion of part 89 extends past bolt 90, and it has a V-shaped recess 91 cut into its inner surface. A lever-yoke 92 is pivoted on the outer end of part 95 of the marker-bar with its ends in position to engage the recess 91 of the other part of the bar. The yoke is U-shaped, it embraces the bar top and bottom, and its ends extend rearward past the rear surface of part 95. A line 93 connects with the looped end of the yoke or U-bar 92, and with the planter-seat or seat-bar it tends to hold the U-bar in engagement with the recess of part 89, and it provides means for raising the marker-bar. This construction enables the part 95 to extend in an approximately horizontal direction at an elevation sufficiently great to permit passage of the check-row wire beneath it, and when the planter reaches an end of the field the entire marker-bar may be raised preparatory to turning and afterward be laid down on the opposite side of the planter. To facilitate this operation, a hook 94 is fastened to line 93 between the ends thereof, and the bar is held raised while the planter is turning by engaging the hook with an eye formed on a side of the driver's seat, as shown in broken lines in Fig. 21. When the planter is turned around, the marker-bar is swung over to the opposite side and the U-bar is disconnected from the notch and reconnected with the other end in engagement therewith, which operation deflects the bar in the proper direction to ride over the wire, and the plowing proceeds. The marker 88 has a draft-line 17, which extends obliquely forward and connects with some convenient portion of the planter-frame, preferably with an equalizing draft-hitch, which forms a feature of the invention and which will now be described as follows:

45 The general tendency of the marker is to create side draft. The tendency varies with the obstructions encountered, and the result is unfavorable to straight driving and straight cross-rows. To overcome the side draft, I 50 provide a swinging draft-hitch for the team and connect the draft-line of the marker-bar with the draft-hitch in a manner to cause the pull of the marker-bar line to shift the center of draft toward the marker. This may be 55 done in different ways, and the specific means herein shown are representative merely of the general idea.

A clevis 14 is pivotally connected at its rear end with the tongue of the planter by means 60 of vertical bolt 15, and the doubletree 13 is swung pivotally in its front end on vertical bolt 14. An eye 16 is swiveled in the front end of the clevis, and with such eye the forward end of the draft-line 17 of the marker 65 connects. The rearward pull of the marker-bar carries the draft-hitch to one side to an extent exactly sufficient to shift the line of

70 draft to the center of resistance, variations in the line of draft occur instantaneously and automatically, as demand arises, and so the 75 planter may be drawn forward in a straight line with one runner as well advanced as the other and without distressing the team by variable side draft. The swiveled eye enables the marker-bar to be swung from side 80 to side of the planter without changing the relation of the draft-line of the marker-bar to the clevis of the draft-hitch.

This feature of the invention is useful in other environments than those described— 85 as, for instance, in a mower or reaper to neutralize the side draft of the sickle-bar.

Another feature of the invention relates to the seed-dropping mechanism, and it resides in a finger which hangs normally in a seed-cell, is carried upward out of the cell by the motion of the seed-disk, strikes a surface at the termination of its upward throw and rebounds forcibly into the next succeeding cell. In this instance the finger 100 forms a continuation of shaft 98, which is pivoted in the cut-off plate 97. It occupies a position in the cut-off space above the seed-disk 101, and it tends to hang downward into a cell 102. The shaft 98 has a knocker extension 99 on its 95 outer end, which also tends to hang downward and away from the under surface of plate 97. When the seed-disk is moved in act of planting, its motion is rapid. A side of a cell strikes the finger and forces it sharply upward until the knocker strikes plate 97, as shown in Fig. 24, and develops a rebound that carries the finger forcibly back into the next succeeding cell and dislodges the grain, if need be, as suggested in Fig. 25. To increase 100 the force with which the finger will enter a cell, an elastic hard-rubber cushion may be set into the plate in position to receive the stroke of the knocker, as suggested at 103 in Figs. 24, 25, and 27. 110

In Figs. 24 and 25 a fragment of the plate under the seed-disk is shown at 104.

The wheel-frame of the planter has a central elevation, as shown in Fig. 15, on which the lifting-levers of the runner-frame are 115 mounted, and straps 85 extend obliquely downward and sidewise to brackets 84 of the runner-frame. When the lifting mechanism is operated through hand-lever 86 or otherwise, the stress is applied equally to both 120 sides of the runner-frame, and such frame is raised or lowered without developing side tilt therein, and when the planter is in operation the oblique straps prevent one runner from entering the ground to a greater depth than 125 the other and so overcome an objection common to wire-actuated planters.

What I claim as new, and desire to secure by Letters Patent, is—

1. In a check-row planter the combination 130 of a reel capable of translatory transposition from one side of the planter to the other, and check-row mechanism adapted to convey the wire to and from the reel.

2. In a check-row corn-planter, the combination of a reel adapted to be mounted on either side of the planter, and a guide to carry the wire across the planter in front of the reel, whereby the check-row mechanism of the planter may be actuated by the wire in act of reeling or unreeling.

3. In a check-row planter, the combination of a cross-wire check-rower having wire-receiving and wire-discharging guides on its ends, and a reel adapted to be mounted on either side of the planter in line with the guides of the check-rower, whereby the wire may pass to or from the reel through the check-rower.

4. In a check-row corn-planter, the combination of a reel, and check-row mechanism the wire-guides of which are swingable across the face of the reel, whereby the wire may be guided to the reel by swinging the wire-guides of the check-rower.

5. In a check-row planter, the combination of a laterally-shiftable reel, and check-row mechanism forming a guide for the reel, substantially as set forth.

6. In a check-row corn-planter, the combination of a laterally-shiftable reel, and check-row mechanism the wire-guides of which are swingable across the face of the reel, whereby the shift of the reel and the swing of the guides may one complement the other, substantially as set forth.

7. In a check-row planter, the combination of a reel-shaft, a reel shiftable lengthwise of the shaft, a relatively stationary guide for the wire and a swingable lever on the reel-frame connected with the reel, whereby the wire may be distributed evenly on the reel by shifting the reel on its shaft, substantially as set forth.

8. In combination with a check-row wire-reel applicable to either side of a planter and driven by a chain running over a smooth pulley, a friction-developing arm, as 31, having chain-bearing surfaces on opposite sides and a central finger to engage the pulley, substantially as set forth.

9. In a wheel-carried implement having a sidewise-extended member, as a planter and marker-bar, a horizontally-swingable draft-hitch at or near the normal center of draft of the implement, and a connection between the sidewise-extended member and the draft-hitch adapted to utilize the resistance of the side member in drawing the draft-hitch toward such resistance, substantially as set forth.

10. In a planter, the combination of a rotatable seed-disk having cells therethrough, a grain-dislodger swung in fixed bearings above the seed-disk in position to enter the cells thereof, and a fixed surface against which the dislodger strikes when it is forced from a cell, substantially as set forth.

11. In a planter, the combination of a rotatable seed-disk having cells therethrough, a finger pivoted in fixed bearings above the line of rotation of the cells, a weight tending to

carry the swinging end of the finger into the cells, and a fixed surface against which the weight strikes when the motion of the seed-plate forces the finger out of a cell, whereby the rebound caused by the weight striking the surface is utilized to carry the finger into the next succeeding cell with a quick, forcible action.

12. In a planter, the combination of a rotatable seed-disk having cells therethrough, a finger pivoted in fixed bearings above the line of rotation of the cells, a weight tending to carry the swinging end of the finger into the cells, and a fixed elastic surface against which the weight strikes when the motion of the seed-plate forces the finger out of a cell, substantially as set forth.

13. In drill-gearing for corn-planters, the combination of a shaft adapted to be driven from a planter-wheel, a crank on the shaft, a pitman on the crank, and an L-lever connected at one end with the pitman and at the other end with the shake-bar of the planter, substantially as set forth.

14. In drill-gearing for corn-planters, the combination of a shaft adapted to be driven from a wheel of the planter, a clutch member on the shaft making and breaking connection therewith by motion longitudinally thereon, a crank in the shiftable clutch member, an L-lever connecting from one end with the shake-bar of the planter, and a pitman on the crank having its extended end recessed in the direction of the motion of the clutch and engaged with the other end of the L-lever, substantially as set forth, whereby the pitman may move with the shiftable clutch member without disengaging the L-lever.

15. In drill-gearing for corn-planters, the combination of a shaft adapted to be driven from a wheel of the planter, a clutch member on the shaft making and breaking connection therewith by motion longitudinally thereon, a crank in the shiftable clutch member, an L-lever connecting from one end with the shake-bar of the planter, a pitman on the crank having its extended end recessed in the direction of the motion of the clutch and engaged with the other end of the L-lever, an obliquely-slotted swingable arm connected with the clutch member, and a finger extended into the slot and partaking of the tilting motion of the wheel-frame in act of raising the runners, whereby the drill-gearing is automatically disconnected from the shake-bar when the runners are raised.

16. In drill-gearing for corn-planters, the combination of a clutch, an upward-extended vertically-swingable arm slotted obliquely and connected with the shiftable member of the clutch, and a finger extended into the slot of the arm and partaking of the tilting motion of the wheel-frame when the runners are raised, substantially as set forth.

17. In a corn-planter, the combination of a rock-frame pivoted centrally and having a pedal at each end, an L-plate, a rod connect-

ing the rock-frame with an arm of the L-plate and a rod connecting the other arm of the L-plate with the shake-bar of the planter, substantially as set forth.

5 18. A check-row arm for corn-planters, comprising a primary bar having a limited amount of horizontal swing on the planter, a secondary bar having a limited amount of horizontal swing on the primary bar and forming a continuation thereof, upward-extended rollers disposed in pairs at the pivots of the bars and the outer end of the secondary bar, and a horizontal wire-guard traversing the space between the upper ends of each pair of rollers and terminating out of contact with one of the rollers, whereby the check-row wire may be raised out of the arm, substantially as set forth.

19. A check-row arm for corn-planters comprising a bracket adapted to be attached to the planter-frame, a block pivoted on the bracket and having downward-extended studs to engage the bracket and limit its swing, a primary bar fixed at one end in the block on the bracket and having a similar block fixed on its swinging end, and a secondary bar pivotally connected with the swinging end of the primary bar in position to be controlled by the studs on the block thereof, substantially as set forth.

20. A check-row arm for corn-planters comprising a primary truss-bar composed of an

upper member and a lower member, and a secondary bar pivotally connected with the primary bar and bearing on an extension of 35 the lower member thereof, substantially as set forth.

21. In a corn-planter, the combination of a runner-frame, a wheel-frame having a central elevation, lifting mechanism for the runner 40 located on the central elevation of the wheel-frame, and straps extending obliquely downward and sidewise from the lifting mechanism to the runner-frame, substantially as set forth.

45 22. A marker-bar for planters composed of two parts pivotally conjoined, an end of one of the parts being recessed and the other part having a swingable stop adapted to engage the recess, substantially as set forth.

23. In a marker-bar for planters, the combination of bar 95, bar 89 pivotally connected with a side of bar 95 and recessed in its end, U-bar 92 embracing bar 95 in position to engage the recess, and a line 93 connected with the 55 U-bar and provided with a hook 94 between its ends, substantially as set forth.

In testimony whereof I sign my name in the presence of two subscribing witnesses.

GEO. D. HAWORTH.
